Levi W. Buxton

UNITED STATES PATENT OFFICE.

LEVI W. BUXTON, OF NASHUA, NEW HAMPSHIRE, ASSIGNOR TO JOSEPHUS BALDWIN AND L. KIMBALL, OF SAME PLACE.

BEDSTEAD-FASTENING.

Specification forming part of Letters Patent No. 23,525, dated April 5, 1859; Reissued June 17, 1873, No. 5,447.

To all whom it may concern:

Be it known that I, LEVI W. BUXTON, of Nashua, Hillsboro county, State of New Hampshire, have invented an Improved Bedstead-Fastening; and I do hereby declare that the following is a full and exact description thereof, reference being had to the accompanying drawings and to the letters of reference marked thereon.

10 To enable others skilled in the art to which my invention belongs, to make and use the same, I will proceed to describe its construction and operation.

Figure 1, of the drawings represents a 15 side view; Fig. 2, a horizontal cross section through the device.

a, represents one of the vertical posts of a bedstead; *b*, one of the rails. The post and rail are both grooved out as seen at *c* and *d*.
20 These grooves are cut out by a circular instrument, so that the grooves in all the posts and rails will be alike and the iron piece *e*, will fit equally well in any of the grooves. This piece *e*, is made with two shoulders *j*, *j*, 25 along the line *x y*, so as to abut against the end of the rail *b*. Part of the edge of piece *e*, is circular and is serrated as seen at *l*, *l*; these little teeth are pressed into the circular top and bottom of the groove *d*, thus making a perfectly tight fit which leaves no room for dirt or vermin to settle in. The end of the piece *e*, which projects into the rail is provided with a hole corresponding to a 30 slightly conical hole in the rail. A conical pin *h*, is driven through these holes in the rail and piece *e*, thus uniting the two parts in a very substantial manner. A pin *g*, is inserted through the post and supports a small friction roller *f*, in the groove *c*. The end 35 of the piece *e*, which projects into the post is made into a hook *e'*, which is to be slipped over the friction roller *f*, when it is desired

to fasten the rail to the post. The circular part of the hook is a little larger than the circumference of the friction roller as seen 45 at *i*, so as to prevent the latter from being jammed. The friction roller serves to ease the insertion of the hook and to allow the hook to slide smoothly down until the circular portion of the hook rests upon the roller, 50 when the rail will be drawn tight up to the post. If the pin *g*, were employed without the friction roller, the friction between the inner surface of the hook and the surface of the pin would work against and impede the 55 insertion of the hook. The hole in the piece *e*, is somewhat larger than the pin *h*, so that only the rear portion of the hole rests against the pin.

It will be seen that the piece *e*, can be 60 easily detached from the rail by simply knocking the pin *h*, out; which is a great advantage in packing.

The posts and rails can be packed nicely 65 in boxes, nothing projecting from the posts or rails that could be knocked off, bent or loosened.

Having described my improved device for 70 fastening bedsteads, what I claim as my invention and desire to secure by Letters Patent, is:

1. The combination of the shoulders *j*, *j*, on the locking or rail piece *e*, with the notched or serrated circular edges *l*, *l*, and conical pin *h*, substantially as and for the 75 purposes set forth.

2. I also claim the combination of the hook *e'*, with the tube or friction roller *f*, and stationary pin *g*, substantially as and for the purposes herein described.

LEVI W. BUXTON.
